UNITED STATES PATENT OFFICE.

ALFRED ANDERSON, OF CAMBRIDGE, MASSACHUSETTS, ASSIGNOR TO
THOMAS W. CARTER, OF BOSTON, MASSACHUSETTS.

ROLL FOR MUSIC-CONTROLLERS.

SPECIFICATION forming part of Letters Patent No. 757,874, dated April 19, 1904.

Application filed July 20, 1903. Serial No. 166,280. (No model.)

To all whom it may concern:

Be it known that I, ALFRED ANDERSON, a citizen of the United States, and a resident of Cambridge, in the county of Middlesex and State of Massachusetts, have invented a new and useful Improvement in Rolls for Music-Controllers, of which the following is a full, clear, and exact description, reference being had to the accompanying drawings, forming a part of this specification, in explaining its nature.

The invention relates to a "controller-roll," so called, for receiving and holding the long perforated controller-sheets used for operating automatically pianolas and similar instruments. Such rolls are used in the playing instruments as a means for holding the controller-sheet while it is being unwound from it and also as a means for receiving the controller-sheet after it has been used and for holding it wound when removed from the machine and not in use. Such rolls have generally been made of wood of a uniform length and with fixed retaining-flanges at each end. They have further been provided at each end with a pin for mounting them in the playing instrument. It has been found, however, that a roll having no provision for extension between the flanges is not desirable, because the paper of the controller-sheet is not always accurately cut to fit the space between the flanges and because the paper varies in width according to the moisture of the atmosphere about it, so that if cut on a dry day to accurately fit the roll-space between the flanges the roll upon a moist day would be somewhat wider and would bind against the flanges sufficiently to interfere somewhat with its unrolling and also subsequently with its rolling up. There would be a tendency to drag in the first instance and to broom up on the edge in the second or to narrow some of the note-perforations by causing the paper to fold or crease along such lines, which are lines of least resistance. On the other hand, paper cut on a moist day to fit the rolls between the flanges would upon a dry day shrink sufficiently to draw away from one or both flanges enough to make the flanges

lose their primary object of governing the position of the strip with respect to the tracker-board. It will be understood, of course, that for good and accurate playing it is essential that the note-perforations in the controller-sheet should always register centrally with the holes of the tracker-board for which they were intended in passing over the board and that any disposition of the paper to expand, contract, or crease which is not controlled is liable to change this relationship of the note-perforations to the tracker-board holes enough to even cause the note-perforations not only to partly register with them, which is not especially desirable, but not register with them at all, which of course would produce discord and is to be avoided. My invention is designed not only to provide means for controlling these vagaries of the controller-sheet, but it also may provide a structure for receiving and holding controller-sheets which intentionally vary in width when such variation is of a limited degree.

I prefer to carry my invention into effect by not departing materially from the common form of roll, and I accomplish this end by first making the roll in the ordinary way—that is, with a wooden spindle for receiving the paper sheet and flanges at each end of the spindle, fixed to it, and the usual pins for mounting the roll in the instrument. The spindle of the roll thus formed is divided into lengths by saw cuts. The cut entering one side of the spindle first curves inward to near the center thereof, then extends outward lengthwise it, then turns upon itself and retraces its course in opposing curves to the opposite side of the spindle, thereby producing in the spindle a somewhat long tongue of the diameter of the spindle in thickness and formed so as to have a narrow portion or neck the lines of which diverge outwardly beyond the neck and then turn inwardly to each other at the extreme end to form a head. The tongue is contained within a recess or cavity of the diameter of the roll, having an enlargement of sufficient size to receive the head of the tongue, a contracted part of a size to receive

the neck of the tongue, and rounded surfaces the reverse in shape of those extending from the neck outward. This gives the spindle an opportunity for elongation between the flanges 5 without separation and without weakening the spindle and also without forming in the surface of the spindle a depressed area of any appreciable extent in it which the first winds of the sheet can enter. The spindle, while it 10 may be elongated, still has its parts held together so that it may not be separated by a longitudinal movement into two parts, the tongue and the recess interlocking to prevent this. Neither is the strength of the spindle 15 materially diminished, so that it may be used in handling the roll as though it were not cut. The cut also is of advantage in many instances, in that it permits the roll to run truer in the machine than if it did not exist, many 20 of the spindles having a disposition to warp out of true after they have been turned; but by the cut described the warped spindle may be used and will run true. I prefer to make the cut on the line of some imperfection or 25 knot and near one end thereof. I also prefer to inclose the spindle at the cut by a short sleeve, preferably of paper, fastened to the spindle upon one side of the cut or the other, as this will tend to strengthen the spindle 30 without interfering with its virtues. The inner end of the sheet is attached, preferably, to the part of the spindle to which the sleeve is secured and to the sleeve. It may or may 35 not be attached to the portion of the spindle which extends beyond the sleeve and to which the sleeve is not secured.

A feature of my invention rendering it peculiarly valuable to the art relates to the manner in which it may be incorporated in 40 spindles of varying lengths. Controller-rolls are made in lengths usually running from eight inches upward to two or more times that amount, although, of course, there are no definite limits. The longer the roll the greater 45 will be the total expansion or contraction of the controller-sheet thereon due to atmospheric changes. It is to be noted that the more tapering or the less abrupt are the curves of the cut dividing my spindle the 50 greater will be the play or relative movement of its two sections for a given clearance or width of cut. Therefore by so dividing the shorter spindles that the curve of the tongue is quite sharply defined and by dividing the 55 longer spindles on lines more nearly parallel to their axes I exactly provide the necessary movement in each case.

I will now describe the invention in conjunction with the drawings forming a part of 60 this specification, wherein—

Figure 1 is a view of the complete roll, representing its structure and also the part which forms the sleeve. Fig. 2 is an enlarged view to better show the portion of the roll to which

the invention relates. Fig. 3 is a view representing the sleeve applied to the roll. Fig. 4 is a view showing the end of the controller-sheet as attached to the spindle and to the sleeve. Fig. 5 is an enlarged view across the spindle and the cuts therein, representing the 70 part which forms the tongue and the part which forms the tongue-holder and also showing the sleeve, the end of a controller-sheet, and a flange.

Referring to the drawings, A represents the 75 spindle of the roll, A' and A² its flanges, and a and a' the pins by which it is mounted in the playing instrument. The flanges are fixed to the spindle, and the spindle is susceptible of elongation by virtue of the recess a², shaped 80 to form upon the section a³ of the spindle the tongue a⁴ and upon the section a⁵ of the spindle the tongue-holder a⁶. This recess may be of such width and shape where desired as to give any desired extent of elongation to the 85 spindle between the flanges A' and A², and the width and shape of the recess govern the extent to which the tongue may be moved lengthwise its holder. The tongue a⁴ is represented in thickness as of the diameter of the 90 spindle and as having curved sides to conform to the curve of the spindle. The tongue has the neck a⁷ and the head or enlargement a⁸, the sides of which are inwardly and outwardly rounded, as represented. The holder a⁶ has the 95 enlargement a⁹ to receive the head a⁸ of the tongue and the contracted part a¹⁰ to hold the neck of the tongue, and the tongue and holder are adapted to slide upon each other. I prefer 100 that the tongue and holder be located near one end of the roll, although this is not necessary.

In order that the two parts of the spindle may be prevented from having the slight lateral movement in the direction of the side surfaces of the tongue, I prefer that the holder and tongue be covered by a sleeve B, preferably of paper of one or more thicknesses and preferably attached to the part a⁵ of the spindle by adhesive material, but not attached to the part a³. While I have represented the sleeve as attached to the part a⁵, it may be attached to the part a³ instead.

The inner end c of the controller-sheet C is 115 preferably attached to the portion of the spindle to which the sleeve B is secured and to the sleeve, although I do not confine myself to this method of attaching it to the spindle.

It will be understood that the controller-sheet serves to automatically vary and control 120 the distance between the two flanges A' and A² of the roll as it is wound upon the roll and that the spindle of the roll elongates or shortens to the variations in the width of the controller-sheet and to the length of the roll 125 in which the sheet is wound; also, that the usual yielding bearing in the playing instrument, which receives and holds the roll while

the sheet is being unwound from it and also while it is being wound upon it after it has been played, serves to exert and maintain a closing pressure upon the two flanges of the roll, whereby one of the flanges while in the machine is caused to be pressed toward the other, and that this assists in maintaining the flanges of the roll in a governing relation to the edge of the controller-sheet while it is being played and also while it is being rewound.

While I have described one method of forming the tongue and its holder in the spindle, I would not be understood as limiting myself to such method, but can use any other that will secure the result above specified.

The possible shapes in which the interlocking tongues and recesses may be cut are too numerous to be mentioned, but they obviously fall within the scope of my invention.

I have implied that the tongue and holder were formed in the spindle after the flanges were attached to the spindle, and while this is a desirable method of providing the roll with means for the variation of its flanges yet the spindle may be provided with the tongue and holder before the flanges are secured to it.

Having thus fully described my invention, I claim and desire to secure by Letters Patent of the United States—

1. A roll for holding music controller-sheets herein described, the same comprising a spindle, flanges and roll-bearing pins, the spindle having means for its elongation or contraction provided by a cut formed therein to separate the spindle into two parts and provide one part with a tongue and the other part with a tongue-holder, the tongue and tongue-holder so formed as to have a restricted movement longitudinally with respect to each other.

2. A roll for holding music controller-sheets herein described, the same comprising a spindle, flanges and roll-bearing pins, the spindle having interlocking means for its elongation or contraction comprising a tongue having a head upon one part of the spindle and a holder shaped to receive and contain the tongue and head upon another part of the spindle, the holder, tongue and head being from side to side of the diameter of the spindle and being shaped throughout to the size of the remainder of the spindle.

3. A roll for holding music controller-sheets herein described, the same comprising a spindle in two parts, each of which has a flange and a roll-bearing, and one of which parts has a tongue and neck formed at its end, and the other of which has a tongue-holder at its end formed to receive and hold the tongue and permit its restricted longitudinal movement therein.

4. A roll for holding music controller-sheets, the same comprising a spindle, flanges and roll-bearing pins, the spindle having interlocking

means for its elongation or contraction and a reinforcing-sleeve applied to the roll over the interlocking means.

5. A roll for holding music controller-sheets, the same comprising a spindle, flanges and roll-bearing pins, the spindle having interlocking means for its elongation or contraction and a reinforcing-sleeve applied to the roll over the interlocking means and secured to the spindle in a manner to permit of said elongation or contraction.

6. A roll for holding music controller-sheets, the same comprising a spindle, flanges and roll-bearing pins, the spindle having integral, interlocking means for its elongation or contraction, and a reinforcing-sleeve covering said integral, interlocking means.

7. A roll for holding music controller-sheets, the same comprising a spindle, flanges and roll-bearing pins, and the spindle having integral, interlocking means for its elongation or contraction, a sleeve covering said means and attached to a portion of said spindle, and a controller-sheet adapted to be wound upon the spindle, attached by its inner end to a portion of the spindle and to the sleeve.

8. A roll for holding music controller-sheets, the same comprising a spindle, flanges, and roll-bearing pins, the spindle being in a plurality of sections, said sections having interlocking means, permitting of their restricted relative movement along the axis of the spindle, and of their free disengagement upon relative movement in another direction.

9. A roll the spindle of which is formed in a plurality of sections, said sections having interlocking means permitting of their restricted relative movement along the axis of the spindle and of their free disengagement in another direction.

10. A roll the spindle of which is formed in a plurality of sections, said sections having interlocking means preventing their relative rotation while permitting of their restricted relative movement along the axis of the spindle and of their free disengagement upon relative movement in another direction.

11. A roll the spindle of which is formed in a plurality of sections, the ends of the opposing sections of shapes to interlock by means of a tongue on the one section and a recess in the other section, said tongue extending from the spindle-section as a relatively narrow shank and broadening beyond the shank, the tongue and recess being of a relative length and shape to provide the sections with a restricted longitudinal movement in either direction for substantially the purpose set forth.

12. A roll for holding music controller-sheets, the same comprising a spindle, flanges, and roll-bearing pins, the spindle having integral, interlocking means permitting of its restricted elongation and contraction and of its free dismemberment upon a relative move-

ment of said means transverse to the axis of the spindle.

13. A roll for holding music controller-sheets, the same comprising a spindle, flanges and roll-bearing pins, the spindle having integral interlocking means permitting of its restricted elongation and contraction and of its free dismemberment upon a relative move-

ment of said means transverse to the axis of the spindle, and a controller-sheet, the inner end of which is attached to the said spindle.

ALFRED ANDERSON.
